Primary Examiner — Jennifer Rivard*Assistant Examiner* — Jonathan E Fiencke*(74) Attorney, Agent, or Firm* — Greer, Burns & Crain, Ltd.(57) **CLAIM**

The ornamental design for a pool grating as shown and described.

DESCRIPTION

FIG. 1 is a perspective view of a pool grating showing the new design, according to a first embodiment;

FIG. 2 is a top plan view thereof;

FIG. 3 is a side elevational view thereof;

FIG. 4 is an opposite side elevational view thereof;

FIG. 5 is a front elevational view thereof;

FIG. 6 is a rear elevational view thereof;

FIG. 7 is a perspective view of a pool grating according to a second embodiment;

FIG. 8 is a top plan view thereof;

FIG. 9 is a side elevational view thereof;

FIG. 10 is an opposite side elevational view thereof;

FIG. 11 is a front elevational view thereof; and,

FIG. 12 is a rear elevational view thereof.

The broken lines depict portions of the pool grating that form no part of the claimed design.
